UNITED STATES PATENT OFFICE.

PAUL G. DURYEA, OF TRENTON, NEW JERSEY, ASSIGNOR TO WOODWARD-WANGER COMPANY, OF PHILADELPHIA, PENNSYLVANIA, A CORPORATION OF PENNSYLVANIA.

DESIGN FOR A BATHROOM FIXTURE.

Application filed October 11, 1928. Serial No. 28,462. Term of patent 14 years.

To all whom it may concern:

Be it known that I, PAUL G. DURYEA, a citizen of the United States of America, and a resident of Trenton, in the county of Mercer, State of New Jersey, have invented a new, original, and ornamental Design for a Bath-Room Fixture, of which the following is a specification; reference being had to the accompanying drawings, forming part thereof, in which—

Figure 1 is a front elevation of the bath-room fixture, showing my new design.

Fig. 2 is a side elevation of said fixture.

Fig. 3 is a plan view of the same.

Fig. 4 is an inverted plan view, and

Fig. 5 is a perspective view looking from the under side.

I claim:

The ornamental design for a bath-room fixture, substantially as shown.

PAUL G. DURYEA.
